UNITED STATES PATENT OFFICE.

HANS MÖRTZSCH, OF DETROIT, MICHIGAN, ASSIGNOR TO MÖRTZSCH AND KLEE, OF DETROIT, MICHIGAN, A PARTNERSHIP.

EXPLOSION-ENGINE.

1,031,809.

Specification of Letters Patent.

Patented July 9, 1912.

Application filed May 9, 1908. Serial No. 431,957.

To all whom it may concern:

Be it known that I, HANS MÖRTZSCH, a subject of the Emperor of Germany, residing at Detroit, in the county of Wayne and State of Michigan, have invented certain new and useful Improvements in Explosion-Engines, of which the following is a specification, reference being had therein to the accompanying drawings.

10 The invention relates to explosion engines and has for its special object the increase in power of the engine without materially increasing the dimensions thereof.

To this end the invention consists in the 15 construction as hereinafter set forth.

In the drawings—Figure 1 is a vertical cross section through the engine; Fig. 2 is a section at right angles to Fig. 1 in the plane of the valves; and Fig. 3 illustrates a 20 slightly modified construction.

My improved construction comprises essentially a cylinder having bores of different dimensions in different portions thereof, and a single piston having portions fitting 25 the respective bores connected by a pitman to a single crank. Both the portion of the cylinder of the small bore and the portion of the larger bore surrounding the smaller piston are employed as explosive chambers, 30 and the general construction and organization of the parts is such that the explosions alternate in the two portions of the cylinder, and consequently an impulse is given for each down stroke of the piston.

35 As illustrated, A is the upper or small bore and B is the lower or large bore of the cylinder, and C and D are portions of the piston respectively fitting said bores. Each portion of this piston is suitably packed, as 40 by the rings E and E', while the body of the piston is hollow and has therein the wrist pin F which is connected to the pitman G. The cylinder is mounted upon a suitable crank case H, within which is arranged the 45 crank shaft I having the crank J, while at one side of the crank is arranged a cam shaft K for operating the valves. These valves are arranged in lateral projections of the engine cylinder respectively communicating with the upper ends of the bores of 50 different diameter. The upper lateral projection L contains the inlet and exhaust valves M and N preferably arranged in the plane of the cam shaft, while the lower

lateral projection L' is provided with similar inlet and exhaust valves M' and N'.

As illustrated in Figs. 1 and 2, the upper and lower valves are out of alinement with each other, but all are arranged in the plane of the cam shaft, and separate cams K' upon this shaft are employed for actuating separate valve rods O for these valves.

In the construction illustrated in Fig. 3, the upper and lower valves are in alinement with each other and are operated by the same cams, the lower valve being operated by a direct rod connection O extending upward from the cams, while the upper valves are operated through the medium of the rod O' extending downward from the lower side of the cams and transmitting their movement through levers P to upwardly extending rods Q connecting with the upper valves. A water jacket R preferably formed integral with the cylinder surrounds both 75 of the bores thereof.

With the construction as described, the valve operating mechanism is so timed as to produce an engine of the four-cycle type, in which the explosions in the respective 80 bores of the cylinder are alternated. Thus there is an explosion for each down stroke of the piston, the suction stroke for the other portion of the cylinder occurring simultaneously. During the upward stroke 85 the products of combustion are expelled from one portion of the cylinder, while the explosive charge is compressed in the other portion of the cylinder. Suitable igniters are arranged for each of the explosion chambers, and these are preferably located as 90 illustrated in Fig. 1.

What I claim as my invention is:

1. In an explosion engine, a cylinder having portions of different diameters, a piston having portions of different diameters fitting the respective portions of the cylinder, lateral projections upon the cylinder above each of the portions of the latter forming independent chambers communicating with the cylinder portions, valve chambers in each of said chambers, inlet and exhaust valves in said valve chambers, igniters communicating with said lateral projections, and means for operating each set of valves alternately whereby the explosions in the respective portions of said cylinder are alternated.

2. In an explosion engine, a cylinder having portions of different diameters, a piston having portions of different diameters fitting the respective portions of the cylinder, lateral projections upon the cylinder communicating with the cylinder portions, valve chambers in each of said projections, inlet and exhaust valves respectively in said chambers, igniters communicating with said lateral projections, and means for operating each set of valves alternately whereby the explosions in the respective portions of said cylinder are alternated.
3. In an explosion engine, a cylinder having portions of different diameters, a water jacket surrounding said portions, a piston having portions of different diameter fitting the respective portions of the cylinder, lateral projections upon the cylinder above each of the portions of the latter forming

independent chambers communicating with the cylinder portions, igniters communicating with said projections, inlet and exhaust valves in each of said projections, a crank case, a cam shaft within the crank case, a 25 plurality of reciprocating rods slidingly journaled in the crank case and extending into operative relation to the valves, the upper and lower valves being out of alignment, and a plurality of cams on said shaft 30 for actuating each set of valves alternately whereby the explosions in the respective portions of said cylinder are alternated.

In testimony whereof I affix my signature in presence of two witnesses.

HANS MÖRTZSCH.
